EASEL HEAD

Burrell V. Hughes, Detroit, Mich.

Application January 25, 1950, Serial No. 7,459

Term of patent 14 years

(Cl. D33—14)

To all whom it may concern:

Be it known that I, Burrell V. Hughes, a citizen of the United States, residing at Detroit, Wayne County, Michigan, have invented a new, original, and ornamental Design for Easel Heads, of which the following is a specification, reference being had to the accompanying drawing, forming part thereof, wherein:

Fig. 1 is a top plan view of an easel head showing my new design.

Fig. 2 is a side elevational view thereof.

Fig. 3 is a bottom plan view of the head.

I claim:

The ornamental design for an easel head, as shown.

BURRELL V. HUGHES.
